(57) **CLAIM**

The ornamental design for a set of brushes with attachable base, as shown and described.

DESCRIPTION

FIG. 1 is a side elevation view of a large size toe brush in accordance with the present invention showing the upper handle with the brush and the detents used to hold the handle in a base.

FIG. 2 is a side elevation view of a medium size toe brush in accordance with the present invention showing the upper handle with the brush and the detents used to hold the handle in a base.

FIG. 3 is a side elevation view of a small size toe brush in accordance with the present invention showing the upper handle with the brush and the detents used to hold the handle in a base.

FIG. 4 is a side elevation view of an upper brush handle with the brush removed from the handle.

FIG. 5 is a side view of the upper toe brush handle shown holding the brush.

FIG. 6 is a front elevation view of the toe brush with a brush mounted in the handle and showing a brush clip in the down, or locked, position.

FIG. 7 is a rear elevation view of the upper brush handle with a brush mounted in the handle.

FIG. 8 is a top view of the upper brush handle with a brush mounted in the handle.

FIG. 9 is a bottom view of the upper brush handle with a brush mounted in the handle.

FIG. 10 is a side elevation view of a short handle with the brush mounted in the handle and with this combination placed over a side elevation view of a brush base which is designed to accept the lower portion of the upper brush handle.

FIG. 11 is a front elevation view of a short handle with the brush mounted in the handle and with this combination placed over a front elevation view of the brush base which is designed to accept the lower portion of the upper brush handle; and,

FIG. 12 is a rear elevation view of a short handle with the brush mounted in the handle and with this combination placed over a rear elevation view of the brush base which is designed to accept the lower portion of the upper brush handle.
